UNITED STATES PATENT OFFICE

92,291

DESIGN FOR A LIGHTING STANDARD

Harry S. Clarke, Long Beach, Calif., assignor to
Fritz Ziebarth, doing business as Southwest
Street Company, Long Beach, Calif.

Application September 18, 1933, Serial No. 49,275

Term of patent 7 years

To all whom it may concern:

Be it known that I, HARRY S. CLARKE, a citizen of the United States, and a resident of Long Beach, in the county of Los Angeles and State of California, have invented a new, original, and ornamental Design for Lighting Standard, of which the following is a specification; reference being had to the accompanying drawing, forming a part thereof;

Figure 1 is a side elevation of my lighting standard.

Figure 2 is a top plan view of the base with the column removed shown to a somewhat enlarged scale.

I claim:

The ornamental design for a lighting standard, as shown.

HARRY S. CLARKE.
